UNITED STATES PATENT OFFICE.

PAUL E. KVISTAD, OF MATLOCK, WASHINGTON.

NECKTIE-VEST.

1,299,582.

Specification of Letters Patent. Patented Apr. 8, 1919.

Application filed August 8, 1918. Serial No. 249,009.

To all whom it may concern:

Be it known that I, PAUL E. KVISTAD, a citizen of the United States, residing at Matlock, in the county of Mason and State 5 of Washington, have made a new and useful Invention which I term a Necktie-Vest, of which the following is a specification.

My invention is an extremely lightweight over garment, the body portion of which 10 consists of a single piece of goods, unopened at the front, adapted to serve as an ornamental front to a shirt, and as an integral part thereof, a necktie, with means for holding the garment smoothly and in place for 15 wearing.

I attain these objects by the devices illustrated in the accompanying drawing, in which—

Figure 1 is a front view of the garment. 20 Fig. 2 is a front view of the garment as it appears on the wearer before necktie is tied. Fig. 3, back view of the garment as it appears on the wearer. Fig. 4, a shorter or modified form of the garment. This also 25 shows the appearance of the tie when formed into a bow.

Similar numerals refer to similar parts throughout the several views.

The main body of the garment consists of 30 the single piece 1, preferably of decorative material. 2 and 2' represent two pieces of tape or similar material stitched to the underside of the garment as shown by the dotted lines, the tapes extending out from 35 either side, as shown. At the ends of the tapes are the rings 3 and 3', of any suitable material, adapted to facilitate the easy adjustment of the garment, or to hold it in place for wearing. 4 and 4' are a series of 40 buttonholes near the ends of the pieces 2 and 2' to afford adjustment in placing the garment in place for wearing. 5 and 5' loops 45 of cloth located on the underside of the garment through which the tapes 2 and 2' pass when garment is in position for wearing. 6 and 6' stiffening material fastened underneath the garment, the scalloped edges of said material projecting beyond the lower 50 edge of the main body of the garment. 7 and 7', stiffening material placed underneath the garment, extending to the edge thereof and from the points a to a and a' to a'. 8, a loop adapted to fit over a collar or shirt button. 9 and 9', a tie of the narrow or 55 string variety fastened to the garment, the

ends of the tie to be inserted through the loops 10 and 10'.

In use, the garment is placed over the breast, the loop 8 attached to the collar or shirt button, the tie is then encircled around 60 the neck, the piece 9' being then placed through the loop 10 and the piece 9 placed through the loop 10'. The tapes 2 and 2' are crossed over the back as shown in Fig. 3 and inserted through the loops 5 and 5' 65 located at the sides and under portion of the garment. The buttonholes 4 and 4' are then buttoned over suspender buttons at the sides, the plurality of buttonholes at 4 and 4' permitting an adjustment to suit the size of the 70 user. The rings 3 and 3' can be used for this purpose if their location is suitable to size of wearer. Fig. 2 shows the tie encircling the neck before the ends of the tie are inserted through the loops 10 and 10', also 75 the tapes 2 and 2' after being crossed at the back, passing through the loops 5 and 5' and fastened to the suspender buttons by the buttonholes 4 and 4'. Fig. 4 shows the tie after 80 being inserted through the loops 10 and 10' and tied in the form of a bow as worn. Fig. 4 also shows a shorter or modified form of my invention, adapted to be worn with the coat buttoned up.

The particular object of the garment is to afford light, cheap, portable and convenient means for putting up a presentable appearance. The full sized garment, when the body portion is of silk, weighs an ounce, of 85 cotton material, a little over an ounce. In 90 the drawings the body 1 is shown plain, but in use it is preferable to have this portion of decorative material not so easily soiled. It can be easily folded up and carried in the pocket. To illustrate one of its uses: A 95 factory worker in a city, whose home may be many miles from his place of work, can carry one of these garments in his pocket and when through work can put this device over his soiled shirt; the front of it being 100 of one piece will cover up the soiled shirt underneath, enabling the wearer to stay downtown or go to a theater, etc., without having to go home to dress up. It can be worn over an undershirt, if desired, and for 105 hot countries would be especially suitable for that purpose. The loop 8 and the fact that the ends of the tie are crossed and inserted through the loops 10 and 10' before tying 110 holds the device in place around the neck.

and it can be worn with the turndown collar of a soft shirt, with a standup collar or without a collar, as the tie forms a double band around the neck. The tapes and other means mentioned serve to hold the garment smoothly over the breast. Its extreme lightness and portability are one of its distinctive features.

Having thus described my invention, what I claim is:

- 10 1. A garment of the class described, comprising a body portion decorative and flexible, adapted to embrace the breast of the wearer, consisting of a single piece, unopened front tapering toward the top, an elastic loop located at the neck portion thereof for fastening the same to a collar or shirt button, a band stitched to each side of the neck portion, said bands adapted to encircle the neck as a tie, loops on the front of the garment adjacent the neck portion adapted to hold the tie in juxtaposition with the front of the body portion when the tie is made into a bow, inelastic lightweight bands stitched to the underside of the body portion adapted to serve as a reinforcement thereto, said bands extending from the sides of the body portion and crossing the back of the wearer, adapted to hold the front of said garment smooth and in position for wearing, a series of buttonholes in the free ends of said bands attachable to the suspender buttons of the wearer for furnishing adjustment and holding said bands in operative position, the whole comprising a flexible garment of extremely lightweight adapted to be folded and carried in small compass when not in use.

- 25
- 30

2. A garment of the class described, having in combination a lightweight, flexible body portion adapted to embrace the body 35 of the wearer, consisting of a single piece unopened front tapering toward the top, narrow sections of stiffening cloth stitched underneath and adjacent to the bottom and upper sides thereof, an elastic loop located 40 at the neck portion thereof for fastening the same to a collar or shirt button, a band stitched to each side of the neck portion, said bands adapted to encircle the neck as a tie of the string bow variety, loops on the 45 front of the garment adjacent the neck portion adapted to hold the tie in juxtaposition with the front of the body portion when the tie is made into a bow, inelastic lightweight bands stitched to the underside of the body 50 portion adapted to serve as a reinforcement thereto, said bands extending from the sides of the body portion and crossing the back of the wearer, adapted to hold the front of said garment smooth and in position for 55 wearing, a series of buttonholes in the free ends of said bands attachable to the suspender buttons of the wearer for furnishing adjustment and holding said bands in operative position, the whole comprising a flexible garment of extremely lightweight adapted to be folded and carried in small compass when not in use.

PAUL E. KVISTAD.
